(57) CLAIM

The ornamental design for an elongated kabob pet treat as shown and described.

DESCRIPTION

FIG. 1 is a front, top, and left side perspective view of an elongated kabob pet treat according to the new design;

FIG. 2 is a left side elevation view thereof;
FIG. 3 is a right side elevation view thereof;
FIG. 4 is a front elevation view thereof;
FIG. 5 is a rear elevation view thereof;
FIG. 6 is a top plan view thereof; and,
FIG. 7 is a bottom plan view thereof.

The broken lines shown in FIGS. 1-7 illustrate portions of the elongated kabob pet treat that forms no part of the claimed design.
